UNITED STATES PATENT OFFICE.

EMMIT G. LATTA, OF SYRACUSE, NEW YORK.

TYPE-WRITING MACHINE.

Serial No. 1,221,875.

Specification of Letters Patent. Patented Apr. 10, 1917.

Original application filed April 12, 1912, Serial No. 690,355. Divided and this application filed January 30, 1914. Serial No. 815,399.

To all whom it may concern:

Be it known that I, EMMIT G. LATTA, a citizen of the United States, residing at Syracuse, in the county of Onondaga and State of New York, have invented a new and useful Improvement in Type-Writing Machines, of which the following is a specification.

This invention relates to typewriting machines having pivoted type-bars that make the impressions at the front side of the platen, and more particularly to improvements in typewriters of this kind in which the type-bars carry different sets of type and are adapted to be shifted for placing one or another set of type in printing relation to the platen. The invention is not, however, necessarily restricted in all of its features to machines of this kind.

This application is a division of my application Serial No. 690,355, filed April 12, 1912.

The objects of the invention are to produce a typewriting machine of a construction such that, owing to the location and construction of some of the parts and their direct action, it produces greater speed and certainty in the escapement and ribbon vibrating mechanisms than has heretofore been accomplished in machines having shifting type-bars; and also to improve typewriting machines in the several respects hereinafter described and set forth in the claims.

In the accompanying drawings, consisting of two sheets:

Figure 1 is a fragmentary longitudinal sectional elevation of a typewriting machine embodying the invention.

Fig. 2 is a fragmentary front elevation of the operating parts of the machine.

Fig. 3 is a plan view, partly in section, of the ribbon vibrating and universal bar mechanism.

Fig. 4 is a fragmentary sectional elevation of the vibrating mechanism in line 4—4, Fig. 3.

Fig. 5 is a fragmentary sectional elevation of a ribbon vibrating mechanism of modified construction.

Fig. 6 is a front elevation partly in section thereof.

Like reference characters refer to like parts in the several figures.

Fig. 1 represents the main frame of

the machine having a top plate *a*; *B* the platen carriage which supports the platen *C*; *D* the carriage escapement; *E* one of the type-bars, which are pivoted in an arc below the platen, so as to swing upwardly and rearwardly to make the impression at the front side of the platen; *F* one of the levers which are operated by the finger keys and connected by links *f* to the type-bars for actuating them. This invention is not concerned with these parts, and they may be of any suitable construction. They are illustrated to show their relation and co-action with the other parts of the machine.

The top plate *a* shown, which is preferably removably secured on the upright sides of the frame in any suitable manner, has an open middle portion spanned by a bridge *a'* which supports a ball-bearing carriage track or guide *a''*. The front portion of the top plate is provided at opposite sides with inclined seats *a'''* on which the ribbon spools (not shown) are arranged in an inclined position so as to deliver the ribbon in line with the ribbon vibrator.

The carriage escapement *D* may be of any suitable construction but it is preferably mounted as shown, on a bearing *d* on the rear central portion of the bridge *a'*, and the shaft of the escapement wheel *d'* is provided, as usual, at its front end with a pinion *d''* which meshes with a rack bar on the carriage. *d'''* is the movable lever or part controlling the action of the escapement wheel.

G represents a support or plate on which the bearing hangers for the type-bars are mounted. Each of the type-bars is provided with two type and the hanger support or plate *G* is preferably mounted so that it can be shifted for placing one or another of the two sets of type in the printing relation with the platen. In the construction shown, the hanger support *G* is pivoted to the front ends of two pairs of arms *g* *g'* which are connected respectively to rock shafts *g''* *g'''* mounted in suitable bearings on the opposite sides of the main frame. The hanger support *G* can be shifted by any suitable means, such, for instance, as a cam lever *g⁴* adapted to be rocked by a shifting key *g⁵* and acting on a roller or part *g⁶* suitably attached to the support.

The type-bars are pivotally mounted on

the support G by separate hangers or bearings H of suitable construction, one of which is shown in each of Figs. 1 and 2.

L represents a curved universal bar which is substantially parallel with the arc of the type-bar bearings and is supported over the bearings in position to be struck by the type-bars as they approach the platen, preferably in the following manner:

- 10 M represents a bar which is secured, for instance, by screws m, Fig. 3, to lugs m' on the upper central part of the plate G and is provided at its ends with cross arms m². In the front and rear ends of these arms, 15 parallel rock shafts m³ m⁴ are journaled which are provided with rigid depending arms m⁵. The universal bar has fixed thereto rearwardly extending arms m⁶ which are pivoted to the said depending rock arms m⁵. The universal bar is thus hung so that it is adapted to be moved rearwardly when struck by any one of the type-bars. A suitable spring m⁷ acts to restore the universal bar to its forward or normal position. The 20 spring shown is connected at opposite ends to an arm m⁸ on the rock shaft m³ and to an arm m⁹ on one leg of the center guide for the type-bars hereinafter described. The universal bar is connected to the carriage escapement for actuating it, preferably 25 as follows:

- N represents a nearly horizontal link pivoted at its front end to the rock arm m⁸ and at its rear end to the depending arm of a bell crank lever n which has a rearwardly extending arm connected by a rod n' to the controlling lever d³ of the carriage escapement. The bell crank lever n is pivoted on a bracket n³ secured to the supporting bridge for the carriage track. As the carriage escapement is mounted on a fixed part of the machine while the universal bar is mounted on the shifting supporting plate G, the link N is pivoted to the bell crank n in a plane midway between the normal and shifted positions of the pivot which connects the link to the arm m⁸, so that the action of the escapement will be the same in both positions of the supporting plate G. 40 By these connections the escapement wheel is released every time the universal bar is moved rearwardly by a type-bar, and the spring m⁷ acts to restore the escapement lever as well as the universal bar to the normal position.

- O represents the vibrating ribbon guide or vibrator, which may be constructed and mounted in any suitable way. The vibrator shown has ears o by which it is slidably retained on a stationary center guide P for the type-bars, and it is pivoted at its lower end to the front end of a vibrator lever Q. The center guide shown has downwardly and rearwardly extending legs p rigidly secured to the bar M, preferably by the se-

curing screws for this bar. The center guide slides up or down in front of the vibrator when the type-bars are shifted to different printing relations to the platen and always retains a fixed position relative to the type-bars.

The vibrator O is also actuated by the universal bar through mechanism, which is constructed as follows:

r and r' represent two arms of different lengths which project from a hub R loosely sleeved on the central part of the rock shaft m³. A nut r² screwed on the shaft m³ and bearing against the hub of the arms r r' retains a tapered stud r³ on the rock arm m⁸ in a hole in the arm r, whereby the arms r r' are locked to the rock shaft m³ so that they will be rocked when the universal bar is actuated. When it is desired to silence the vibrator, the nut r² is unscrewed, when a spring r⁴ between the arms m⁸ and r will disengage the latter arm from the stud r³. The arms r r' can be relocked to the rock shaft by again screwing up the nut r².

S represents a link arranged with its front end between the arms r r' and extending rearwardly therefrom with its rear end between correspondingly spaced arms s s' of different lengths depending from the ribbon vibrating lever Q, which is pivoted on the bracket n³. The arms r r' are provided with inwardly extending round-ended pins s² s³ adapted to enter registering holes in the front end of the link S, and the arms s s' have similarly arranged pins s⁴ s⁵ adapted to enter registering holes in the rear end of the link S. In the position of the link shown in the drawings it engages the pins of the short arm r' and long arm s' and connects these arms. By moving the link sidewise it is disengaged from the pins s² s³ and is engaged with the other pins s⁴ s⁵, thereby connecting the long arm r to the short arm s. Thus by shifting the link S sidewise one way or the other, the vibrator lever can be given a short or a long throw suitable for using either of two different ink fields on the ribbon. The pins s² s⁵ are of such length that the link does not leave one pair of pins until the other pair has partly entered the holes in the link, thus insuring the ready shifting of the link. When, however, the link is in operative connection with one pair of arms, the other pair is left perfectly free. The link is shifted sidewise for changing the throw of the vibrator by a plate s⁶ provided with upwardly extending arms having slots s⁷ in which the link S is held from sidewise movement but is permitted to reciprocate freely lengthwise. The shifting plate is slidably secured on the bar M, for example, by a screw s⁸, Fig. 3, passing through a slot in the plate, and has an extension s⁹ ending in an upturned finger piece located in a convenient position for moving

the shifting plate to shift the link S. The extension s^3 is provided with a tooth or projection on its lower side adapted to snap into either one of two notches s^{10} , Fig. 3, in the bar M for holding the plate with the link in engagement with either pair of arms. Any other suitable shifting means for the link S can be used.

5 The pins for the link S are located so that when the type-bars are shifted the operative pin at the front end of the link will be moved from a position below the plane of the operative pin at the rear end of the link to a corresponding distance above that plane, and thus produce like movements of the ribbon in both positions of the type-bars.

10 As seen in Fig. 1, the vibrator lever Q is curved downwardly and the track supporting bridge is recessed above the lever to enable the lever to move the desired distance in the limited room available. The link S is also curved downwardly so as not to interfere with the lever Q when the parts are shifted for upper case work.

15 Figs. 5 and 6 show a ribbon vibrating mechanism which is interchangeable with the vibrating mechanism first described. The universal bar and its supporting shafts m^3 and m^4 are the same as described, and the 20 vibrator lever Q and escapement connections are also the same, but instead of the connected arms r and r' used in the first construction, arms U U' are used which are independently mounted on the shaft m^3 and 25 are spaced by being seated in slots in a sleeve u which is pinned or otherwise secured to the shaft. The arm u' for the restoring spring m^7 and the link N is made integral with the sleeve u . Two separate links u^2 30 and u^3 take the place of the single double acting link S first described, and they are permanently pivoted to the arms U and U' at their front ends, and to the arms q and q' of the vibrator lever at their rear ends. Two 35 short sleeves v and v' are mounted to slide on the shaft m^3 outside of the sleeve u . Pins v^2 and v^3 project inwardly from these sleeves, and each sleeve has a flat spring v^4 rigidly secured to its lower side. These 40 springs contact at their ends and each spring has a tooth or projection to snap into the notches along the underside of the sleeve u . The sleeve u has a hole for the pins v^2 v^3 extending throughout its length, parallel with 45 the shaft m^3 , and pin holes in the arms U U' register with the pins when the parts are in normal position. As shown in Fig. 6, the pin v^3 is in place to lock the arm U' to the shaft m^3 and vibrate the upper field of the 50 ribbon to and from the printing point. To vibrate the lower field it is only necessary to push in the sleeve v as far as it will go, which, owing to the contacting ends of the 55 springs v^4 , pushes the other sleeve v' out of the locking position and releases the arm U' at 60

the same time that the arm U is locked to the shaft m^3 . In order to silence the vibrator, it is only necessary to withdraw the locking pin from whichever arm may be in use, without pushing in the other locking pin. 70 Both arms U and U' with the links u^2 u^3 vibrate together at all times when either arm is locked to the shaft m^3 , and whichever arm is locked controls the movement of the other arm through the arms q q' and the idle link. 75 The pivots at the ends of the links u^2 and u^3 are located in the same positions as the four pins that connect the link S with the arms r r' and s s' in the first construction, and the same result is accomplished in both 80 cases.

I claim as my invention:

1. In a typewriting machine, the combination with a platen and a series of pivoted type-bars, of a support for the type-bars 85 which is shiftable to place the type-bars in different printing relations to the platen, a one-piece curved universal bar which shifts with said support and is arranged to be actuated by the several type-bars as they approach the platen, a device to be actuated at each type stroke which is mounted in fixed position, and an operating connection connected to said device and to said universal bar constructed and arranged to produce 90 like action of said device in both positions of said support, substantially as set forth.

2. In a typewriting machine, the combination with a platen carriage, a series of pivoted type-bars, and a device to be actuated at each type stroke, of a support for the type-bars which is shiftable to place the type-bars in different case printing relations to the platen, a one-piece curved universal 100 bar which is arranged to be actuated by the direct impact of the several type-bars as they approach the platen and is shiftable with the type-bar support, and means connected to the universal bar and to said device constructed and arranged to correspondingly 105 operate said device in the different printing positions of the type-bars.

3. In a typewriting machine, the combination with a platen, and a series of type-bars arranged to strike the front of the 115 platen, of a universal bar arranged to be actuated by the type-bars as they approach the platen, a rock shaft having downwardly extending arms connected to the universal bar, an upwardly extending arm on the rock 120 shaft, a lever pivoted in a fixed position and having a downwardly extending arm in rear of said rock shaft arm, and a link connected to the rock shaft arm and to said lever arm, substantially as set forth.

4. In a typewriting machine, the combination with a platen, and a series of type-bars arranged to strike the front of the platen, of a universal bar arranged to be actuated by the several type-bars, a rock shaft 130

having downwardly extending arms connected to the universal bar, a lever pivotally supported in a fixed position and having a downwardly extending arm, an upwardly extending arm on said rock shaft, a link connected to said upwardly extending arm and to said downwardly extending lever arm, and means for shifting the type-bars, universal bar, and rock shaft in a way to change the location of the front end of said link from a position below its rear end to a position equally distant above its rear end, substantially as set forth.

5. In a typewriting machine, the combination with a platen carriage, a series of pivoted type-bars, and a device to be actuated at each type stroke, of a shiftable support for the type-bars, a universal bar which is arranged to be actuated by the several 15 type-bars as they approach the platen and is shiftable with the type-bar support, a rock shaft mounted on said shiftable support and having arms connected to the universal bar, and means connecting said rock 20 shaft to said device to correspondingly operate the same in the different printing positions of the type-bars.

6. In a typewriting machine, the combination with a platen and a series of type-bars, of a universal bar arranged to be actuated by the type-bars, a rock shaft having arms pivotally connected to the universal bar, a shiftable support for the type-bars and rock shaft, an arm on the rock shaft, a lever pivoted in fixed position in rear of said arms, a link connected to said arm of the rock shaft and to said lever, and means for shifting said support to change the front end of said link from a position below the 30 plane of its rear end to a position equally distant above its rear end, substantially as set forth.

7. In a typewriting machine, the combination with a platen, and a series of type-bars arranged to strike the front of the platen, of a ribbon vibrator lever pivotally mounted below the platen, a universal bar arranged to be actuated by the type-bars, a rock shaft which is rocked by the universal 40 bar and has two pivots located at different distances from the axis of the shaft, and a link for transmitting motion from said rock shaft to said vibrator lever, said link being connectible to one or the other of said rock 50 shaft pivots for changing the throw of said ribbon vibrator.

8. In a typewriting machine, the combination with a platen, and a series of type-bars arranged to strike the front of the platen, of a ribbon vibrator lever pivotally mounted below the platen and having an arm provided with pivots located at different distances from the lever fulcrum, a universal bar arranged to be actuated by the 60 type-bars, a rock shaft which is rocked by

the universal bar, and a link for transmitting motion from said rock shaft to said vibrator lever, said link being connectible to one or the other of said pivots of the vibrator lever for changing the throw of said 70 lever, substantially as set forth.

9. In a typewriting machine, the combination with a platen, and a series of type-bars arranged to strike the front of the platen, of a ribbon vibrator lever pivotally mounted 75 on a fixed part below the platen and having two pivots on one of its arms, a universal bar arranged to be actuated by the type-bars, a rock shaft having downwardly extending arms pivotally connected to the universal bar 80 and having two pivots, and a link whereby either of the rock shaft pivots may be operatively connected to one of the vibrator lever pivots at will, substantially as set forth.

10. In a typewriting machine, the combination with a platen, and a series of type-bars arranged to strike the front of the platen, of a bell crank ribbon vibrator lever pivotally mounted on a fixed part below the platen and having two pivots on one of its arms, a universal bar arranged to be actuated by the type-bars, a rock shaft having downwardly extending arms pivotally connected to the universal bar and having two pivots over its central part, a link whereby 95 either of the pivots over the rock shaft may be operatively connected to one of the vibrator lever pivots, and means for connecting one of said pivots with and simultaneously disconnecting the other pivot from the 100 link at will, substantially as set forth.

11. In a typewriting machine, the combination with a platen and a series of type-bars arranged to strike the front of the platen, of a bell crank ribbon vibrator lever 105 pivotally mounted on a fixed part below the platen and having two pivots on one of its arms, a universal bar arranged to be actuated by the type-bars, a rock shaft having downwardly extending arms pivotally connected to the universal bar and having two pivots over its central part, a link whereby 110 either of the pivots over the rock shaft may be operatively connected to one of the vibrator lever pivots, and a shiftable support 115 for the type-bars, universal bar, and rock shaft acting to move the pivots over the rock shaft from one side to the other of the plane of the vibrator lever pivots, substantially as set forth.

12. In a typewriting machine, the combination with a platen, and a series of type-bars arranged to strike the front of the platen, of a ribbon vibrator lever pivotally mounted below the platen and having an arm extending substantially vertically, a universal bar arranged to be actuated by the type-bars, a rock shaft having arms pivotally connected to the universal bar and having two pivots at different distances from the 125 130

- axis of the shaft, and linkage whereby either 70 of the rock shaft pivots may be operatively connected to the vibrator lever arm, substantially as set forth.
- 5 13. In a typewriting machine, the combination with a platen, and a series of type-bars arranged to strike the front of the platen, of a ribbon vibrator lever pivotally mounted below the platen and having a depending arm, a universal bar arranged to be actuated by the type-bars, a rock shaft having arms pivotally connected to the universal bar and having two pivots at different distances above it, linkage whereby either 75 of the rock shaft pivots may be operatively connected to the vibrator lever arm, and means for disconnecting said operative connection of both of the rock shaft pivots, substantially as set forth.
- 10 14. In a typewriting machine, the combination with a platen, and a series of type-bars arranged to strike the front of the platen, of a bell crank ribbon vibrator lever pivotally mounted below the platen, two pivots on one 80 of the arms of the vibrator lever at different distances from the lever pivot, a universal bar arranged to be actuated by the type-bars, a rock shaft having downwardly extending arms pivotally connected to the universal 85 bar, a pivot arranged over the rock shaft and operatively connected thereto, a link connected to the rock shaft pivot and having two bearings for the pivots of the vibrator lever, and means for shifting the link from one 90 vibrator lever pivot to the other, substantially as set forth.
- 15 15. In a typewriting machine, the combination with a platen and a series of type-bars arranged to strike the front of the platen, of a bell crank ribbon vibrator lever pivotally mounted below the platen, a universal bar arranged to be struck by the type-bars, a rock shaft having downwardly extending arms pivotally connected 95 to the universal bar, and two pivots located at different distances from the axis of the rock shaft, a link having two pivot bearings at its front end and adapted to connect either of the rock shaft pivots to the vibrator 100 lever, and means for shifting the link from one rock shaft pivot to the other, substantially as set forth.
- 20 16. In a typewriting machine, the combination with a platen, and a series of type-bars arranged to strike the front of the platen, of a bell crank ribbon vibrator lever pivotally mounted below the platen, a universal bar arranged to be actuated by the type-bars, a rock shaft having downwardly extending arms connected to the universal 105 bar, and a link having two interchangeable pivots connections with the rock shaft and vibrator lever whereby two different motions may be given the bell crank, substantially as set forth.
- 25 17. In a typewriting machine, the combination with a platen, and a series of type-bars arranged to strike the front of the platen, of a ribbon vibrator lever pivotally mounted below the platen, a universal bar, 110 a rock shaft vibrated by the universal bar, a link having two optional connections with the rock shaft and vibrator lever, and means for shifting the link from one connecting position to the other, substantially as set forth.
- 30 18. In a typewriting machine, the combination with a platen and a series of pivoted type-bars, of a support for the type-bars which is shiftable to place the type-bars in 115 different printing relations to the platen, a one-piece curved universal bar which shifts with said support and is arranged to be actuated by the several type-bars as they approach the platen, a ribbon vibrating device which is mounted in fixed position, and an operating connection connected to said device and to said universal bar constructed and arranged to produce like action of said device in both positions of said support, substantially as set forth.
- 35 19. In a typewriting machine, the combination with a platen carriage, a ribbon vibrating device, and a series of pivoted type-bars, of a shiftable support for the type-bars, a one-piece curved universal bar which is arranged to be actuated by the several type-bars as they approach the platen and is shiftable with the type-bars, and means 120 connected to the universal bar and to said ribbon vibrating device constructed and arranged to be shifted by the shifting of the type-bar support to different positions to correspondingly operate the ribbon vibrating device in both positions of the type-bars, substantially as set forth.
- 40 20. In a typewriting machine, the combination with a platen, and a series of type-bars arranged to strike the front of the platen, of a universal bar arranged to be 125 actuated by the type-bars as they approach the platen, a rock shaft having downwardly extending arms connected to the universal bar, an upwardly extending arm on the rock shaft, a ribbon vibrator lever pivoted in a fixed position and having a downwardly extending arm in rear of said rock shaft arm, and a link connecting the rock shaft arm to said lever arm, substantially as set forth.
- 45 21. In a typewriting machine, the combination with a platen, and a series of type-bars arranged to strike the front of the platen, of a universal bar arranged to be 130 actuated by the type-bars, a rock shaft having downwardly extending arms connected to the universal bar, a ribbon vibrator lever pivotally supported in a fixed position and having a downwardly extending arm, an upwardly extending arm on said rock shaft, a link connecting said upwardly extending

arm to said downwardly extending lever arm, and means for shifting the type-bars, universal bar, and rock shaft in a way to change the location of the front end of said link from a position below its rear end to a position equally distant above its rear end, substantially as set forth.

22. In a typewriting machine, the combination with a platen and a series of type-bars, of a universal bar arranged to be actuated by the type-bars, a rock shaft having an arm connected to the universal bar, a shiftable support for the type-bars and rock shaft, an arm on the rock shaft, a ribbon

vibrator lever pivoted in fixed position in 15 rear of said arms, a link connecting said arm of the rock shaft to said lever, and means for shifting said support to change the front end of said link from a position below the plane of its rear end to a position 20 equally distant above its rear end, substantially as set forth.

Witness my hand, this 26th day of January, 1914.
